ATTORNEY.

UNITED STATES PATENT OFFICE.

AUGUST J. WEIL, OF NEW YORK, N. Y.

CAR-AXLE BEARING.

SPECIFICATION forming part of Letters Patent No. 628,971, dated July 18, 1899.

Application filed August 27, 1898. Serial No. 689,639. (No model.)

To all whom it may concern:

Be it known that I, AUGUST J. WEIL, a citizen of the United States, and a resident of New York, in the county of New York and State of New York, have invented certain new and useful Improvements in Car-Axle Bearings, of which the following is a specification.

My invention relates to a certain new and useful improvement in bearings for car-axle boxes, and particularly to the construction of the key thereof.

Heretofore, so far as I am aware, it has been usual to employ a key for holding a separate bearing-piece securely in position in the box, the key and bearing-piece being made in two distinct parts and connected together in various ways.

The object of the present invention is to simplify the construction of the car-axle bearings by casting the key and the bearing-piece in one integral part and of such a character that it may be changed in its details of construction to adapt it to boxes and brasses of different kinds.

In the accompanying drawings I have illustrated the invention in a simple form, referring to which—

Figure 1 is a longitudinal sectional view of a car-axle box embodying my invention. Fig. 2 is a bottom plan view of the key. Fig. 3 is a detailed enlarged sectional view of one end of the key.

Referring to the drawings, in which like letters of reference denote corresponding parts in all the figures, A designates the journal-box, which may be of any well-known construction, the particular form illustrated being employed by me here simply for the purpose of showing the application of the invention. The brass C is arranged within the box to engage the axle B in the usual manner, and this brass has heretofore been maintained in its proper relation to the axle by means of a separate bearing-piece interposed between the brass and a key secured within the box and having a certain freedom of movement in the key; but by my present invention the brass is held in its proper position by my peculiarly-formed key D. This key consists, preferably, of a substantially flat plate provided with side lugs F to engage corresponding lugs inside of the box and a projection or

heel G, which engages the lug H on the inner side of the top of the box. The manner of securing the key within the box by means of the aforementioned lugs is common in the art, and it will be understood, of course, that I do not limit myself to any particular method of securing the key in place.

On the lower face of the key and integral therewith is a circular concaved recessed bearing-surface I, which receives the circular convexed portion of the brass in the manner clearly illustrated in Fig. 1, and the arrangement is such that while the key is maintained securely in place in the box the convexed portion of the brass may move easily and freely in the recessed concaved portion of the key so far as the same may be necessary while the axle is in action.

As I have heretofore stated, the particular construction of the details of my improved key may be varied as desired, the essential feature of the invention comprising a key provided with an integral bearing-surface to engage the brass, and this bearing-surface is preferably of a circular concave form to accommodate the corresponding circular convex bearing-surface of the brass. It is obvious that the edges of the concaved bearing-surface may be extended below the lower face of the adjacent portions of the key or they may be flush therewith, as desired, and other changes in the details of construction may be made without departing from the spirit or sacrificing the advantages of the invention. It will thus appear that by casting the key and the bearing-surface which engages directly with the brass in one piece I reduce the number of parts necessary in the car-axle bearing and avoid all the disadvantages of a number of working parts which have heretofore been connected together in various ways and which are liable to become bound in wrong positions and otherwise get out of order.

In the drawings I have shown the brass provided with a convex bearing-surface and the key with a corresponding concave bearing-surface; but I do not limit myself to this particular arrangement, for it is obvious that the brass may have the concave bearing-surface and the key provided with the convex bearing-surface.

Having thus fully described my invention,

what I claim as new, and desire to secure by Letters Patent, is—

In a car-axle box, the combination with a brass having a circular convex bearing-surface on its upper side, of a key adapted to be secured within the box and provided on its under side with an integral circular concave bearing-surface complementary to the bearing-surface on the brass and forming, substantially, a ball-and-socket joint, whereby the bearing-surfaces are capable of a rocking

movement in any direction and a lateral movement, one within the other, substantially as described.

Signed at New York, in the county of New ¹⁵ York and State of New York, this 26th day of August, A. D. 1898.

AUGUST J. WEIL.
